UNITED STATES PATENT OFFICE.

EMANUEL WOODINGS, OF OAKMONT, PENNSYLVANIA, ASSIGNOR TO WOODINGS FORGE & TOOL COMPANY, OF VERONA, PENNSYLVANIA, A CORPORATION OF PENNSYLVANIA.

RAIL ANCHOR.

Application filed February 18, 1926. Serial No. 59,069.

This invention relates to rail anchors.

The objects of the invention are to provide a rail anchor that will engage the base of a rail in such manner as to present great resistance to slipping of the rail through the anchor. More particularly, the object is to provide an anchor so formed and so held on the rail that there may be an edge or line engagement of the anchor with the underside of the rail with the result that the force tending to cause the rail to creep through the anchor will exert a turning moment on the anchor and so cause the edge of the anchor to bite into and positively engage the rail, preventing or at least strongly resisting movement therebetween.

Referring to the drawings, Fig. 1 illustrates a cross tie and a rail supported thereon, with one of my anchors applied in operative position to the rail; Fig. 2 is an enlarged vertical cross section on the line II-II of Fig. 1; Fig. 3 is a horizontal section on the line III-III of Fig. 2, the rail being removed but indicated diagrammatically; Fig. 4 is a plan view of the rail anchor, the rail being indicated diagrammatically; Fig. 5 is a section on the line V-V of Fig. 2; Fig. 6 is a section on the line VI-VI of Fig. 2, projections of side elevations of the end of the anchor at each side of the section, being indicated; Fig. 7 is similar to Fig. 2 showing a modification in the rail anchor; Fig. 8 is a section on the line VIII-VIII of Fig. 7 with projected side elevations as in Fig. 6; and Fig. 9 is an end view showing another modification, applied to a rail and tie as in Fig. 1.

Rail anchors are applied to the bases of rails, with a gripping engagement therewith, for the purpose of forming an abutment against the side of a tie to prevent creeping of the rail under the force of trains moving thereover. The general purposes and functioning of such devices are well known in the art, and need not be set forth here.

One of the troubles with rail anchors of the prior art is that they have only a frictional engagement with the undersides of rails, and consequently when heavy trains are moved over them the rails slide through the anchors in spite of the frictional en-

gagement therewith. The anchor now to be described is intended to overcome this difficulty at least to a large degree, by providing an abutment which will not only have a frictional engagement with the underside of the rail, but which will tend under working conditions to actually bite into and form a positive engagement therewith.

In Fig. 1 there is illustrated a standard rail R seated on a wooden cross tie T, with one of my anchors A applied thereto. This anchor is intended to prevent creeping of the rail toward the right, as indicated by the arrow. It will be understood that to prevent creeping in the other direction a similar anchor may be applied with its ends reversed, on the other side of the same or another cross tie.

The anchor itself is formed of good quality bar steel of about .60% carbon. It is shaped to form a resilient bend 1 at its middle portion. At the left of the bend, as illustrated in Fig. 2, the bar has a straight seating portion 2, extending outward to the edge of the rail, an upwardly extending portion 3, and an inwardly bent end 4. On the other side of the middle bend 1 the bar forms a second seating portion 5, a second resilient bend 6, and then it is bent upward and inward to form a terminal 7. The upper sides of the bar above the portions referred to as 2 and 5 are formed into straight plane faces 8 and 9, respectively. These faces as illustrated in Figs. 1 to 8 are inclined at an angle of from five to eight degrees with respect to what would be normal to the side or edge plane of the bar. This inclination of the bearing faces is produced by the forming dies in a preliminary operation on the bar.

In Fig. 9 an anchor A" of uniform thickness in the portions corresponding to 2 and 5 of Fig. 2 is shown. That is to say the upper faces for contact with the under side of the rail are surfaces of a rectangular bar, consequently perpendicular to the planes of the sides of the bar.

On the inner face of the terminal portion 7 of the anchor A there is a notch N, formed by a side face 11 and an upper face 12 substantially perpendicular to the face 11, as illustrated particularly in Fig. 6. This

notch runs obliquely across the inner face of the bar, compared to a perpendicular between the planes of the side faces of the bar.

- 5 The underface of the end 4 of the anchor is adapted to seat flat upon the upper surface of the rail base, when the upper face 12 of the notch engages the opposite upper face of the rail base, as illustrated in Fig. 2.
- 10 That is to say the face 12 of the notch N and the underface of the terminal portion 4 are both adapted to seat flat on the upper side of the rail base when the anchor is applied in normal canted position.
- 15 The anchor is applied to a rail by first engaging its left end on a rail base, and then by a suitable tool bending outward the other end 7 until it will slip over the lower corner of the base of the rail at the right, and then 20 forcing it upward until the upper face 12 of notch N seats upon the upper face at the corner of the rail, as shown in Fig. 2. The resiliency of the clamp and the engagement of the notch will then hold the anchor in 25 place, the clamp being held at a slight incline to the plane of the rail base, as shown in Fig. 1. Consequently, the faces 8 and 9 on the upper side of the body portion of the anchor will contact with the underface of 30 the rail at their forward edges only, i. e. the left side when positioned as indicated in Figs. 1, 5, etc. The face of the anchor opposite this contacting edge is positioned so that it abuts the side of a tie, as shown in 35 Fig. 5.

When a train passes in the direction indicated by the arrow in Figs. 1, 5, and 9, the tendency of the rail to creep forward with the train and the abutment of the anchor 40 against the tie apply a turning or canting movement to the anchor, and the contacting corners or edges of the faces 8 and 9 tend to bite into the underside of the rail base, and so to form a positive engagement therewith, as 45 compared to a mere frictional contact. The tilted position at which the rail anchor is held as shown in Fig. 5 further aids this tendency, as will be apparent.

In Figs. 7 and 8 there is illustrated a 50 modification, in that instead of the notch N for locking the anchor in position upon the rail, I provide a projection 20. The underface of this projection is inclined with respect to a perpendicular between the side 55 planes exactly as is the upper face 12 of the notch N, and with the same results of tilting the anchor slightly so as to cause the forward edge only of the anchor to engage the underside of the rail. In all other respects 60 the construction and operation of the anchor A' is the same as that illustrated in the other figures, and described above.

In order to increase the tendency of the 65 forward edges to bite into the underside of the rail, and to give greater leverage for

the turning moment exerted by abutment with the tie, the lower portion of the anchor may be bent slightly backward, as illustrated in Fig. 9. In that case particularly the faces 8 and 9 may be made perpendicular to the 70 side planes of the upper portion of the anchor. That is to say the special shaping of the faces that are to engage the underside of the rail may be omitted. The same is true of the forms shown in Figs. 2 and 7, 75 but those forms are more effective with the inclined portions provided as described.

It will be understood that a tie plate P is ordinarily used between the rails and the ties, also that most ties are rounded off at 80 the corners, as shown in Figs. 1 and 9. Consequently, even without the bending back of the lower part of the anchor as shown in Fig. 9, the abutment of the anchor against the tie is materially below the level of the 85 underside of the rail, so that a substantial turning moment fulcruming on the biting edges of the faces 8 and 9 is exerted when the rail tends to move forward through the 90 anchor.

I claim:

1. A one-piece rail anchor adapted to extend under a rail and to be retained on the base thereof, having a plurality of faces adapted to engage the underside of the rail 95 at points spaced inward from the edges of the rail and at the forward edges only of the faces, and means to hold the anchor with the edges in engagement with the underside of the rail.

2. A rail anchor adapted to extend under a rail and to be retained on the base thereof having a plurality of inclined intermediate faces formed by bends in the anchor and adapted to engage the underside of the rail 105 at the forward edges of the faces, and integral means to hold the anchor with the said edges in engagement with the underside of the rail.

3. A rail anchor adapted to be held in 110 engagement with the base of a rail by its own resiliency, the anchor having a plurality of faces formed by bends in the anchor adapted to engage the underside of the rail, and integral means to hold the anchor in 115 position with the said inclined portions engaging the underside of the rail at their forward edges only.

4. A rail anchor adapted to be held in engagement with the underside of a rail by its 120 own resiliency, the anchor having inclined faces adapted to engage the underside of the rail, and means to hold the anchor in position with the said inclined faces engaging the underside of the rail at their forward 125 edges only.

5. A rail anchor adapted to engage at each end the upper corners of the base of a rail, one end of the anchor having a rail base engaging abutment adapted to en- 130

gage the upper corner of the rail and shaped to hold the anchor at an oblique angle to the plane of the base of the rail, whereby to press the forward edge only of the anchor against the lower face of the rail.

6. A rail anchor adapted to resiliently engage the base of a rail, means to hold the anchor with the forward edge only thereof

in engagement with the underside of the rail, and an extension of the anchor adapted to abut a tie positioned beneath the rail, the lower edge of said extension being bent toward the tie whereby to fulcrum the anchor on the forward edge thereof.

In testimony whereof, I sign my name.
EMANUEL WOODINGS.
